UNITED STATES PATENT OFFICE.

ALLISON N. CLARK, OF PLAINVILLE, CONNECTICUT.

TAG.

SPECIFICATION forming part of Letters Patent No. 236,983, dated January 25, 1881.

Application filed October 21, 1880. (No model.)

To all whom it may concern:

Be it known that I, ALLISON N. CLARK, of Plainville, in the county of Hartford and State of Connecticut, have invented certain new and 5 useful Improvements in Tags, of which the following is a specification.

My invention relates to improvements in tags, in which the tag proper is formed upon the end of a piece of wire and in conjunction 10 with a spring-ring, also formed upon said wire; and the objects of my improvements are, first, to provide a ring which can readily receive a bunch of watch-keys or other articles, while the tag will indicate their number or the size 15 of the hole; and, second, to produce the same at a trifling cost. I attain these objects by the simple construction illustrated in accompanying drawings, in which—

Figure 1 is a front elevation, and Fig. 2 a 20 side elevation.

a designates the tag proper, which is formed by flattening the wire at that end, preferably by means of a die formed with the desired figure upon it, so that the figure designed to be raised 25 upon the tag may be made simultaneously with flattening the wire. In this manner the dies may be made of such form as to produce the same figure upon the opposite sides of the tag.

In the drawings the figure 4 is represented 30 upon the tag; but any desired figure or figures may be placed thereon.

If desired, the tag may be made with a simple flattened end, without any figures thereon, and any desired figure, number, or letter may 35 be afterward stamped thereon in any desired manner. From the flattened or tag end the wire extends straight for a short distance, when it

is bent into the form of a spring-ring, *c*, and preferably with an outward-turned end, as at *b*, to facilitate slipping articles upon the ring. 40

The article may be put to a variety of uses, but it is chiefly designed for putting up watch-keys, in which case a dozen or more of a certain size may be slipped upon the ring, with the number indicating the size stamped upon 45 the tag. This manner of putting up watch-keys is more economical than placing them on a card, and it is also a much more convenient way for the jeweler or retailer of the keys.

Other forms of spring-rings may be followed without departing from the main features of my invention, the essential feature of which consists of the tag formed upon the piece of drawn wire, from which a spring-ring is also formed by coiling the opposite end of 55 the wire.

Instead of receiving a number of articles, the ring may be used as a means of securing the tag to a single article only.

I am aware that a prior patent shows a key-ring blanked out from sheet metal, which ring has a broad surface upon one side for a name-plate, and I hereby disclaim the same.

I claim as my invention—

The herein-described article, consisting of 65 the tag *a*, formed on one end of a piece of wire, and the coiled-wire spring-ring formed on the opposite end of said piece of wire, substantially as described, and for the purpose specified.

ALLISON N. CLARK.
